UNITED STATES PATENT OFFICE.

ALFRED SHEDLOCK, OF NEW YORK, N. Y.

ROCK-DRILLING MACHINE.

SPECIFICATION forming part of Letters Patent No. 254,393, dated February 28, 1882.

Application filed December 10, 1881. (No model.)

To all whom it may concern:

Be it known that I, ALFRED SHEDLOCK, of the city of New York, county and State of New York, have invented certain new and useful Improvements in Rock-Drilling Machines, of which the following is a specification.

This invention relates to that class of rock-drilling machines designed to be operated by hand-power; and it consists of certain improvements in the supporting-legs, whereby the machine may be readily adjusted in working position; of improvements in the construction and arrangement of the striking-hammer and its actuating-spring, whereby the hammer has a direct linear movement to and from the drill-holder, and the spring may be easily removed to be substituted by a stronger or weaker one, as the quality of rock operated upon may demand; of an improved device for actuating the drill to and from the bottom of the hole and partly rotating it between each successive blow, so constructed as to obviate the necessity of using spring-pawls or springs, and to make said movements of the drill perfectly positive; of an improved feeding device for carrying the drill forward as fast as it performs its work; and it further consists of such improvements in the general construction and arrangement of the various parts that the same are not liable to get out of order, there being no bolts or nuts in the machine to jar loose.

To enable others skilled in the art to which my invention appertains to make and use the same, I will now refer to the accompanying drawings, forming part of this specification, in which—

Figure 1, Sheet 1, is a longitudinal central sectional elevation. Fig. 2, Sheet 2, is a plan view. Fig. 3, Sheet 3, is a part side elevation, showing another form of hammer-actuating device and springs, and also a modification in the feeding device. Fig. 4, Sheet 3, is a plan view of Fig. 3. Fig. 5, Sheet 3, is an enlarged transverse section of the same cut through the line xx . Fig. 6, Sheet 3, illustrates another method of holding the hammer-spring in position. Fig. 7, Sheet 1, is a transverse section cut through the line yy , Fig. 1, looking toward the face of the hammer. Fig. 8, Sheet 2, is a transverse section on the same line, yy , looking in the opposite direction. Fig. 9, Sheet 1, is a trans-

verse section cut through the line zz , Fig. 1. Fig. 10, Sheet 2, is an enlarged view, partly in section, showing the drill-turning device slightly modified in form. Fig. 11, Sheet 2, is an enlarged transverse section of the leg-clamping device; and Fig. 12, Sheet 3, represents the manner in which the three legs are attached to the rear end plate for upward drilling.

The frame consists simply of the rear end piece, a , and the side bars, a' and a'' , secured at one of their ends thereto. The end piece, a , is provided with three short rods. Two of them, a^3 a^4 , project at the sides and the other one, a^4 , at right angles to them. It is also shown with a pad, a^5 , against which the operator may press when using the machine. The bar a' is pointed at its front end, and the bar a'' is provided with an adjustable point, a^6 , screwed on the end of it, to accommodate irregularities in the rock, and that both bars, a' and a'' , may bear with equal pressure when the machine is adjusted to drill in the desired direction. The three supporting-legs are alike. They each consist of a straight rod, b , which passes through a hole in the bolt b' , laterally enlarged, as shown at Fig. 11, and at right angles to this laterally-enlarged hole is formed another hole, partly in the head of the bolt b' , adapted to receive the short rods a^3 a^4 of the end piece, a , and the end of the side bar, a' .

Between the rod b and bar a' , or rods a^3 a^4 , are placed two washers, b^2 and b^3 , having partly-circular recesses to embrace their respective rods, and the contact-faces of these washers are preferably roughened or radially corrugated to prevent them shifting when the legs are set; or a friction-washer may be placed between. On the bolt b' , beyond the rod b , is placed the washer b^4 , and on its extreme end is the tightening-nut b^5 . By means of this arrangement of parts each leg may be set in any position by simply loosening the nut b^5 , the rod b then being free to slide longitudinally through the bolt b' and washers b^3 b^4 to adjust the machine as to height, and free to move sidewise in the laterally-enlarged hole in the bolt b' to adjust the rod b in an angular position in one direction, the angular position in the other direction being provided for by the bolt b turning on the rods a^3 or a^4 or bar a' , on which it is placed; and when set as desired

all parts are firmly held by simply tightening the nut b^5 .

- In Figs. 1, 2, 7, and 9 a leg is shown on each of the short rods a^3 of the rear plate, a^2 , and the third one on the front end of the side bar, a' . This is the disposition of the legs when the machine is operating into the face of a rock, from which it will be seen the machine is self-sustaining. The object of the third short rod, a^4 , on the plate a is to enable the leg on the end of the bar a' to be used in upward drilling, as shown in the diagram sketch, Fig. 12, or in downward drilling, the plate a being then in reverse position to that shown in Fig. 12.
15. The working parts of the machine, with the exception of the hammer, are contained in or connected to the body or frame e , composed of the cylindrical shell, girders e^1 , and end piece, e^2 , and bearings e^3 , e^4 , which fit freely on the bars a' , a^2 . In bearings on the cylindrical part of the body e is fitted to rotate the feed-screw d , which passes through the nut-frame e , adapted to be clamped in any desired position on the bars a' and a^2 by the set-screws e' , 20 closing the split bearings on the bars. In this frame e are pivoted the two half-nuts e^2 , which are closed down on the screw d by springs e^3 . It will be observed that this screw has a ratchet-shaped thread, the object of which is to prevent any injury to the screw or half-nuts if the hammer be allowed to act against the drill-plunger when the end of the drill is away from the rock, and it permits the body and drill to be pushed forward, the springs of the nuts e^2 25 allowing them to slide over the thread of the screw d in the one direction. The ends of the half-nut project above the frame e , and one of them has pivoted to it the cam-lever e^4 , which, when pressed down between their ends, separates the nuts from the screw d , leaving the body of the machine free to be moved on the bars a' , a^2 when it is desired to withdraw the drill from the hole or to set the machine for a continuation of the feed after the screw d has 30 moved the body as far forward as it can, which resetting is accomplished by slackening the set-screws e' of the nut-frame e and moving the nut-frame forward on the bars a' and a^2 , to be again secured thereto, and the half-nuts e^2 allowed to embrace the screw d by throwing 35 back the cam-lever e^4 .
- The screw d is provided with a head, d' , which bears against its front bearing, and has secured to its other end the toothed wheel or disk d^2 , 40 which bears against its rear bearing, so that while free to be rotated it has no longitudinal play. It is actuated by the pawl d^3 , pivoted on the top of the yoke f , fitted in a groove turned in the plunger f' , to the front end of which the drill f^2 is secured. This plunger f' has a reciprocating motion imparted to it by means hereinafter described, said motion varying in extent according to the work done by the drill. The pawl d^3 moves with the plunger f' , and 45 being cam-shaped near its end, which is provided with the projection d^4 , adapted to catch in the teeth of the wheel d^2 , said end is caused

to move laterally as the pawl is drawn backward by the cam working over the roller or stud d^5 on the body e , and it is held thereto by the spring d^6 . The front edges of the teeth of the wheel d^2 are pointed, as shown, and the projection d^4 lies beyond these teeth when the pawl is in its extreme forward position. Now, assume the pawl to be in the position shown in the drawings and to be drawn back by the plunger f' , the projection d^4 enters the space between the two lower teeth, and as the pawl rides over the roller or stud d^5 the projection d^4 carries the wheel d^2 one tooth forward, and so partly rotates the screw d and feeds the drill forward a distance in excess of the greatest depth it is capable of cutting at one blow, the blow of the hammer being imparted to the drill just before it, with the plunger f' , is moved back; and if this blow has not caused the drill to cut the maximum depth, then when the plunger f' moves forward, carrying with it the pawl d^3 , the projection d^4 will remain in the space between the teeth it previously entered, and so slide backward and forward therein until the plunger f' is allowed to make its forward maximum movement. Then the projection slips over beyond the front edge of the next tooth, and the pawl d^3 is moved laterally back by the spring d^6 against the roller or stud d^5 , bringing the projection d^4 again into position to catch into the succeeding space of the wheel d^2 when the pawl is next moved back by the plunger f' . The pressure of the spring-acting half-nuts e^2 on the screw d will in most cases be sufficient to hold the screw d and toothed wheel d^2 from jarring back or moving too far ahead; but to insure the teeth of the wheel d^2 being in proper position for the pawl d^3 to actuate it, I propose to arrange an ordinary spring pawl or catch, d' , to engage in the teeth of the wheel d^2 , as shown in Figs. 2 and 11.

In the modification of the feeding device shown at Figs. 3, 4, and 5 the wheel g on the screw d has face ratchet-teeth. The pawl g' is caused to slide backward and forward by the plunger f' in a similar manner to the pawl d^3 . The projection on the pawl g' is caused to enter one of the ratchet-teeth of the wheel g by the pin near its pivotal center striking against the fixed bracket g^2 , when the pawl, with the plunger, moves into the extreme forward position, and when the plunger moves back the pawl g' moves into the angular position, as shown by the dotted lines in Fig. 4, and so turns the wheel g one tooth. The pawl remains in this last position until it is again knocked back by the bracket g^2 , as shown.

The drills of this class of machine have heretofore been pressed back against the bottom of the hole by means of a spring after being moved therefrom to receive a partial rotation. Now, in this machine the drill is actuated both as regards its to-and-fro motion and rotation by means of positive-acting devices, so that the minimum of power is required to operate this part of the machine and the liability of derangement entirely avoided. A good prac-

tical way of carrying this out is as follows: The rear end of the plunger f' is fitted to rotate in the head h , which is provided with a sleeve, h' , fitted in the end of cylindrical part 5 of the body c , and this head has a positive reciprocating motion imparted to it from the driving-shaft i by means of the two sets of cams i' and i^2 , acting respectively against the vertically-projecting bearers h^2 and h^3 .

10 Referring now to the enlarged view, Fig. 10, the plunger f' has secured to its rear end the worm-wheel j . Outside the bearing in the head h and on the plunger is shown a collar, f^3 , located near the end of the sleeve h' , allowing the plunger a little play longitudinally in the head h , which will about equal each forward movement due to the feed, so as to prevent the cam i' binding in the head h when they move the head and plunger f' forward, should 15 the drill strike the bottom of the hole before the head has completed its full movement, the plunger being so moved forward by the end of the sleeve h' striking the collar f^3 and moved back by the worm-wheel j striking the other 20 end of the bearing in head h . Instead of the collar f^3 , the end of the slot in the sleeve h' , through which the upper part of the yoke f passes, may be used to move the plunger forward with the head.

25 In some cases—as, for instance, in upward drilling—it may be advantageous to employ a small spring to hold the worm-wheel j to the end of the head h . In such case, where the construction of the head h as shown at Fig. 10 is used, I propose to place said spring between the yoke f and the shoulder of the head h , reducing the plunger in this part to accommodate the spring; or the spring h^4 may be placed outside the worm-wheel j and the head 30 h made in two parts and screwed together to form a box for the spring, as shown at Figs. 1 and 8.

Between the cams i' and i^2 , and forming one piece therewith, is the worm-cam j' , having 35 connecting-ribs, which rotate in the spaces of the worm-wheel j to positively hold it and the plunger from rotating, excepting when one of the worm-cams j' (of which there are two) is operating to turn the wheel j , which takes 40 place just after the cams i^2 have withdrawn the drill from the bottom of the hole. It will be observed that the worm-wheel j , being carried by the head h , changes its position under the worm-cam j' ; but the teeth of the worm-wheel j and worm-cam j' are so shaped as to 45 properly work together during such movement of the wheel j . As the cams i' i^2 are double-acting, the drill is withdrawn and partly rotated twice during each revolution of the shaft i .

50 Shaft i has bearings in the girders c' of the body c , and is rotated by the crank-handles k . Secured to the shaft just outside the bearings in the girders c' are the two throw-cams l . These cams operate the striking-hammer m by 55 acting on the rollers m' m' . The hammer in this machine is adapted to slide on the side bars, a' a^2 , of the frame by the bearings m^2 m^3 ,

so that it has a direct lineal movement to and from the end of the plunger f' . The striking-plug n of the hammer is concave on its face, 70 and the plug n' , secured in or to the end of the plunger f' , is correspondingly convex, as more clearly shown in Fig. 6, the plug n' being detached. The object of so shaping these striking-plugs is to obviate as much as possible the spreading of them from the continual blows by providing them with considerable contact-surface, and the concavity of the plug n tends to cause the plug n' to retain its shape. The concavity and convexity of the plugs n and n' 75 may be reversed.

80 One of the main features of this invention is the method of applying the striking-spring to the machine, the object being to secure it in place, without employing any screws or bolts 85 therefor, in such a manner that all possibility of its getting loose is obviated, besides providing for the ready removal of the same and replacing it by another spring of different strength when desired. Several forms of springs 90 are shown, but they are all retained in position in substantially the same manner between the front side of the end pieces, c^2 , of the body c and the rear side of the hammer m .

95 In Figs. 1, 2, and 7 an elliptic spring, o , is shown, the ends of the leaves of which are bent round and connected together by hooking said round ends over the pins of the yoke-pieces o' o' , one of the pins being separable from its yoke, to be inserted through it and the corresponding 100 rounded end of the spring after the other three rounded ends have been placed over their pins in the yokes. The centers of the two sides of the elliptic spring o are punctured and fit over the studs c^2 and c^3 on the end piece, c^2 , and hammer m . The spring is placed in position by passing it between the girders c' of the body and end piece, c^2 , and hammer m , and compressing it to allow the two sides to spring over the 105 studs c^2 and c^3 .

110 Bow-springs p p' , made of flat steel, are shown in Figs 3 and 4, held in place by simply passing their rounded ends over bars p' p' , formed on the end piece, c^2 , and hammer m . This form of spring is preferable in most respects to the elliptic spring, and the simplest manner of securing it in place is that shown in Fig. 6, where the ends of the bow-spring q are merely bent at right angles to fit into recesses q' and q^2 , formed in the center of the hammer m and end piece, c^2 . One spring only is 115 here shown. Two springs may be used—one above, the other below—if thought best; but one spring will be sufficient to impart the required impetus to the hammer m , as said form of springs may be made of any strength desired. From the foregoing it will be seen that the spring maintains its position between the hammer m and end piece, c^2 , by reason of its resilience only.

120 It is advantageous that the working parts of machines of this description should be protected from the grit and dust, &c. To enable this to be done I propose to continue the ribs 125

of the girders c' so as to meet the rear bearing of the feed-screw d , as shown at Figs. 3 and 4, thus forming the three sides of a box in which most of the working parts are contained, and the top covered by a wrought or cast metal plate bent down in front of the cams and plunger, and provided with a hole, through which the striking-plug of the hammer may pass. A plate may be cast on the body to form the bottom of the box.

To enable the hammer-actuating device to be also placed in the inclosing box, I propose to substitute for the ordinary cams $l l$ the arms $r r$, provided at their ends with the rollers $r' r'$, which, when the arms are rotated, come in contact with the ends of the arms $s s$, projecting from the front of the hammer m , as shown at Figs. 3 and 4, and so move back the hammer against the springs $p p$. It will be observed that these arms $r r$ occupy much less space than the cams $l l$, and may be placed inside the girders $c' c'$, as shown, and formed, if desired, in one piece with the cams $i' i^2$, and j' . The front bearing of the hammer is shown at the ends of the arms $s s$, thereby increasing the length of the hammer bearing on the side bars, $a' a^2$, of the frame. This form of hammer-actuating device is in some respects superior to the cams $l l$, and may be placed outside the girders $c' c'$, as are the cams $l l$.

It will be observed from the preceding description and from reference had to the drawings that in this machine no nuts or bolts are employed in the construction of it; so the liability of any of the parts becoming deranged or being lost is obviated, which derangement or loss of parts is very liable to happen to machines of this class in which nuts and bolts are used, on account of the continuous jarring they are subjected to.

Having now described my invention, what I claim, and desire to secure by Letters Patent, is—

1. In an adjustable leg for rock-drilling machines, a straight supporting-rod adapted to slide through a bolt fitted at right angles on a rod or a bar of the frame, clamping-washers between the straight supporting-bar and said rod or bar, and a nut on the end of the bolt for clamping the whole together, substantially as described.

2. In combination, the straight supporting-rod b , the bolt b' , having two holes at right angles through it, one of which is laterally enlarged, the clamping-washers $b^2 b^3 b^4$, the nut b^5 , and the rod or bar of the frame, adapted to pass through the plain hole in the bolt, substantially as set forth.

3. A frame for rock-drilling machines, composed of the two side bars, $a' a^2$, the one, a' , of which is pointed and the other one, a^2 , provided with an adjustable point, the end pieces, a , having the three short rods $a^3 a^3 a^4$, in combination with three adjustable supporting-legs, two adapted to be connected to the short rods $a^3 a^3$ and the other to the front end

of one of the side bars, a' , and also to the short rod a^4 , substantially as and for the purpose set forth.

4. A frame for rock-drilling machines, composed of a rear end piece and two side bars, on which the body and operating parts of the machine slide, the front end of one of the side bars being pointed and the other one being provided with an adjustable point, substantially as and for the purpose set forth.

5. The body c , composed of a cylindrical shell, in which fits the drill-holding plunger, an end piece, c^2 , the connecting-girders $c' c'$, provided with bearings for the driving-shaft, and the bearings $c^3 c^4$, by which the body c is supported and free to slide on the side bars of the frame of the machine, substantially as set forth.

6. In a rock-drilling machine, a body carrying the operating mechanism and adapted to slide on the side bars of the frame, a hammer, also adapted to slide on the said side bars between one end of the main portion of the body and an end piece connected thereto by girders, and a spring located between the hammer and end piece of the frame, and adapted by its resilience to drive the hammer against the end of a plunger fitted in the main portion or cylindrical shell of the body, substantially as and for the purpose set forth.

7. The combination, with a sliding hammer and end piece of the body, of a spring adapted to be secured to the hammer and end piece and maintain its position between them by reason of its resilience only, substantially as set forth.

8. The curved flat spring q , in combination with the end piece, c^2 , having the recess q^2 , and the hammer m , having the recess q' , substantially as set forth.

9. In combination, the body $c c' c' c^2 c^3 c^4$, the hammer m , with the actuating-cams on the shaft i , and the spring q , substantially as set forth.

10. The striking-plug of the hammer, having a concave face, in combination with the plug at the end of the drill-plunger, having a convex end, substantially as and for the purpose set forth.

11. A drill-holding plunger fitted to slide in the body of the machine, and operated to reciprocate to move the point of the drill to and from the bottom of the hole positively in both directions by means substantially as described, and actuated from the driving-shaft.

12. A drill-holding plunger fitted to slide in the body of the machine, and operated to reciprocate to move the point of the drill to and from the bottom of the hole positively in both directions by means substantially as described, and actuated from the driving-shaft, in combination with a compensating-spring.

13. A drill-holding plunger fitted to slide and rotate in the body of the machine, in combination with means, substantially as described, for positively moving the drill to and from the

- bottom of the hole, and means, substantially as described, for intermittently rotating the same when away from the bottom of the hole.
14. In combination, the plunger f' , sliding head h , having bearers h^2 h^3 , worm-wheel j , and cams i' i^2 , whereby the plunger f' is caused to move to and from the bottom of the hole positively in both directions, substantially as described.
15. In combination, the plunger f' , sliding head h , having bearers h^2 h^3 , cams i' i^2 , worm-wheel j , and worm-cams j' , whereby the plunger f' is caused to move to and from the bottom of the hole positively in both directions, and be positively rotated when away from the bottom of the hole, substantially as described.
16. In combination, the plunger f' , adapted to receive a reciprocating movement after each blow of the hammer thereon, the worm-wheel j , and worm-cams j' , substantially as described.
17. In combination, the drill-holding plunger f' , sliding head h , cams i' i^2 , worm-wheel j , and spring h^4 , whereby the head h is allowed to move a short distance after the drill has reached the rock, substantially as set forth.
18. In a rock-drill, a body carrying the operating parts of the machine and adapted to slide on the two side bars of the frame, in combination with the feed-screw fitted to rotate in bearings on the body, and a nut-holding frame adapted to be adjusted in position on and secured to the said side bars, substantially as set forth.
19. A feed-screw for rock-drilling machines, having a ratchet-shaped thread, substantially as and for the purpose set forth.
20. In combination with a ratchet-shaped thread feed-screw fitted in bearing on the body, spring-acting half-nuts, carried by a frame con-
- nected to the main frame of the machine, substantially as set forth.
21. In combination, the screw d , the toothed wheel d^2 , the spring-acting pawl d^3 , the yoke f , the roller or stud d^5 , and plunger f' , substantially as set forth.
22. In combination, the screw d on the body and the half-nuts e^2 , provided with the springs e^3 , and the nut-frame e , substantially as described.
23. A drill-holding plunger fitted to slide in the body of the machine, and operated to reciprocate to move the point of the drill to and from the bottom of the hole positively in both directions by means substantially as described, and actuated from the driving-shaft, in combination with a compensating-spring and a feeding device constructed and operated to feed the machine forward as fast as the drill cuts, substantially as set forth.
24. A drill-holding plunger fitted to slide in the body of the machine, and operated to reciprocate to move the point of the drill to and from the bottom of the hole positively in both directions by means substantially as described, and actuated from the driving-shaft, in combination with a compensating-spring, a feeding device constructed and operated to feed the machine as fast as the drill cuts, and a spring-acting hammer, substantially as set forth.
- In witness whereof I have hereunto set my hand, at New York, county and State of New York, this 8th day of December, A. D. 1881.

ALFRED SHEDLOCK.

In presence of—
 E. G. BAKER,
 H. D. WILLIAMS.
